X-RAY-PROOF GLOVE

Morris Lubow, Brooklyn, N. Y., assignor to Wolf
X-Ray Products Inc., New York, N. Y., a corpo-
ration of New York

Application October 17, 1941, Serial No. 415,363

10 Claims. (Cl. 250—108)

This invention relates to improvements in gloves of the kind used by the operators of X-ray apparatus to shield their hands against the effects of the X-rays during the use of the apparatus.

Heretofore, X-ray proof gloves have proven unsatisfactory, for they are made of lead impregnated rubber of a thickness of substantially one-sixteenth of an inch thick, provided with an inner fabric lining and an outer leather covering. The above mentioned thickness is essential to carry the amount of lead necessary for producing a safe ray-proofing material. This construction is stiff and prevents the free and easy flexing of the fingers of the glove, which is essential to the comfort of the wearer and to the tight gripping of articles picked up by the glove. Thus, the thickness of the lead impregnated glove body is necessary for protective purposes, and it is the purpose of this invention to retain the safe protective thicknesses of the walls of the lead impregnated glove body, while reducing the stiffness thereof to render the same more flexible and responsive to the natural movements of the fingers of the hand of a wearer.

Another feature of the invention resides in an X-ray proof glove in which the required protective thickness of lead impregnated rubber is divided into two thicknesses which are in free contacting engagement except at their outer edges where they are secured together. By reason of the free contact of the rubber plies or thicknesses throughout substantially their entire surfaces, the rubber glove body is rendered more flexible than if the rubber were of a single thickness equal to the combined thickness of the two plies.

A further feature of the invention is to provide an X-ray proof glove in which the needle holes caused by stitching the impregnated rubber plies together are covered by lead impregnated rubber binding tape, as well as other adhesively connected joints, to prevent the penetration of the X-rays through the needle holes, and to strengthen the glove at the joints.

Another feature of the invention is the provision of an X-ray proof glove which is simple and inexpensive of construction, easy to put on and take off, and capable of long life.

Other novel features of the invention will become apparent as the following specification is read in conjunction with the accompanying drawings, in which,

Figure 1 is a perspective view of the finished

X-ray proof glove constructed in accordance with the invention, with a portion of the outer covering broken away to expose a portion of the inner glove unit.

5 Figure 2 is a perspective view of the inner lead impregnated rubber glove body.

Figure 3 is an enlarged horizontal sectional view on the line 3—3 of Figure 2, the outer leather covering being illustrated in dot and dash lines.

10 Figure 4 is a view similar to Figure 3 taken through one of the rubber glove fingers on the line 4—4 of Figure 2.

Figure 5 is a plan view of the trunk from 15 which the lead impregnated rubber glove body is constructed, one of the corners of the trunk being folded back to disclose the several plies of material from which it is constructed.

Figure 6 is an enlarged detail vertical sec- 20 tional view on the line 6—6 of Figure 5.

Figures 7 and 8 are plan views of the blanks from which the back of the second and third fingers are formed.

25 Figure 9 is a plan view of the blank from which the thumb of the ray-proof glove is formed.

Figure 10 is a rear view of the inner lead im- 30 pregnated glove body with a portion broken away.

Figure 11 is an enlarged detail vertical sec- 35 tional view on the line 11—11 of Figure 10.

Figure 12 is an enlarged detail sectional view on the line 12—12 of Figure 2.

Referring to the drawings by reference char- 40 acters, and at present to Figure 1 of the drawings, 10 designates my improved X-ray proof glove in its entirety, and which broadly includes an inner lead impregnated glove unit or element 11, as shown per se in Figure 2, and which is enclosed within an outer leather glove ele- 45 ment 12. The glove 10 is provided with the usual four fingers and a thumb, and is of a length to cover the hand, wrist, and a portion of the forearm of the wearer in order to protect these parts against harmful effects of X-rays. Gloves of this type are worn by X-ray operators and physicians in the operation of X-ray apparatus, and the administering of X-rays to a patient.

The inner glove element or unit 11 is con- 50 structed from a trunk, shown in plan in Figure 5, and which trunk is designated A. The trunk A consists of a plurality of sheets of lead impregnated rubber, two of which are shown, the inner sheet being designated 13, and to one side of the sheet 13 a fabric lining sheet 14 is adhesively se-

cured as at 15, although the lining may be stitched to the sheet 13 if desired. Disposed against the other side of the inner lead impregnated rubber sheet 13 is an outer lead impregnated rubber sheet 16. The lead impregnated sheets 13 and 16 are of the same thickness and are substantially $\frac{1}{2}$ of an inch thick each, making a total thickness of lead impregnated rubber amounting to $\frac{1}{4}$ of an inch. Heretofore, it has been the practice to use a single ply of lead impregnated rubber of $\frac{1}{16}$ of an inch thick, for it has been proven that such thicknesses of the rubber is essential in a material of this kind to support the amount of lead required to prevent the passage of X-rays. It is a known fact that a sheet of X-ray proof material $\frac{1}{16}$ inch thick should, for safety purposes contain .5 millimeter of lead through the thickness of the rubber, and I employ two sheets of such ray-proof material, each of $\frac{1}{32}$ inch, each sheet containing approximately .3 millimeter of lead throughout the thickness of the rubber. It will be understood that the trunk A is cut to the shape shown in Figure 5 from the plies 13, 14, and 16, when they are in superposed relation. The front trunk section B is slit as at 17 to receive the thumb member presently to be described. The trunk A is divided when folded on the fold line 18 into the front glove section B and a rear glove section C, the fold line extending the length of the trunk midway of its sides. The front glove section B is provided with four finger portions 19, 19a, 19b, and 19c, the first and last finger portions 19 and 19c being complementary with the first and last finger portions 20 and 20a respectively of the section C so as to meet when the trunk A is folded upon itself on the fabric lining side, such side being shown up in Figure 5.

The rear glove section C has only the two rear finger portions 20 and 20a integral therewith, and the same are slightly wider and longer than their related front finger portions 19 and 19c to provide additional material sufficient to provide open fingers when they are brought together and stitched as best illustrated in Figure 4, and which added material is the equivalent to the four chettes of an ordinary glove. The second and third finger portions are respectively designated 20b and 20c and the blanks from which they are constructed are of the same thicknesses of lead impregnated rubber and fabric as the trunk and are shown in Figures 7 and 8. The rear finger portions 20b and 20c are related to and are respectively connected to the front finger portions 19b and 19a when the glove is completed. However, before the trunk is folded upon itself on the dotted line 18, the bottom ends of the finger portions 20b and 20c which are reduced in width, are placed inlapping relation with respect to the edge 31 of the crotch between the finger portions 20 and 20a and the lapping portions adhesively secured together as at 32, as illustrated in Figure 11. After the finger portions 20b and 20c are adhesively secured to the rear section C, a strip of lead impregnated rubber tape 33 is applied over the joint to provide additional ray proof protection and strengthen the joint between these parts.

A thumb member 22 is inserted through the opening 17 from the inside of the trunk and is constructed and secured in position in a manner now to be explained. The thumb member 22 is constructed of a single blank D shown in Figure 9 and which is cut to double thumb shape as shown. The thumb blank D is constructed of two plies of lead impregnated rubber 13a and 75

16a, and an inner lining of fabric 14a, and the inner side of the blank along its lower edge is scived to provide a beveled attaching edge 34. The blank D is folded inwardly upon itself along the medial dotted line 35 and the top and side free meeting edges are stitched as at 24. A protective and strengthening strip of lead impregnated rubber tape 26 is applied to the stitched edges as illustrated in Figure 2. The scived portion 34 is applied to a mating scived portion 35 provided on the front section B about the edge of the opening 17 on the inside thereof and these meeting scived portions are adhesively secured together by cement 25. The cemented joint is strengthened and protected by a strip of lead impregnated rubber tape 26' which overlaps the same and is adhesively secured thereto.

After the trunk A has been cut in the manner just described and the finger portions and thumb portion are secured thereto, it is folded inwardly upon itself on the dotted line 18, after which the free side edges of the sections B and C opposite to the folded side are secured together by stitching 21. The stitching 21 also extends about the free edges of the finger portions 19, 19a, 19b, 19c and the corresponding edges of the finger portions 20, 20c, 20b, and 20a, respectively. Thus, it will be seen that the lead impregnated rubber sheets 13 and 16 of the front and rear sections B and C are secured together only along their outer edges whereby these sheets are free substantially over their entire areas in order to render the rubber glove unit 11 more flexible than if the lead impregnated rubber were one sheet of $\frac{1}{16}$ of an inch.

The stitching 21 leaves needle holes in the front and back sections of the glove, through which needle holes, X-rays may pass. However, the needle holes are sealed by a single lead impregnated binding strip 26a which is adhesively secured to the outer rubber sheet 16 adjacent the respective free stitched edges. The binding strip 26a is of a width to overlap the stitching on both sides of the edges as best illustrated in Figure 3 of the drawings. The operations just described produce the lead impregnated rubber glove unit 11 which is provided with a hand entrance opening 27 where the edges of the several sheets of material are left free.

The outer leather glove covering 12 is constructed similar to a conventional leather glove and is provided with four fingers 28 and a thumb 29. The outer glove covering 12 is of a size to snugly receive the rubber glove element 11, and the glove element 11 is inserted into the outer glove covering 12 with the fingers and the thumb member of the element 11 extending into the corresponding fingers 28 and thumb 29 of the outer leather glove element 12. After the element 11 has been inserted into the element 12, the two elements are stitched together as at 30 adjacent the hand entrance opening to prevent separation of these two glove elements. However, it will be noted that the rubber glove element 11 is free within the corresponding parts of the glove element 12, their only point of connection being at the hand entrance opening where they are secured by the stitching 30.

By reason of the novel construction set forth above, there is produced an X-ray proof glove which is relatively flexible due to the construction of the inner lead impregnated rubber glove element 11 being made of a plurality of relatively thin thicknesses of material rather than from a single relatively thick sheet of lead impregnated

rubber. By reason of increasing the flexibility of a glove of this construction, it is possible for the wearer to more freely flex the fingers of the glove to facilitate the handling of articles when the wearer is subjected to the harmful rays of an X-ray apparatus. Also, the method herein shown and described permits the inexpensive manufacture of an X-ray proof glove.

Whereas I have specifically mentioned two plies of relatively thin impregnated rubber are used in the making of the rubber X-ray proof glove, the same may be made of additional plies, providing the relative proportion of lead to the thickness of the rubber is adhered to in order to render the material impervious to X-rays. Also, the finger portions 20b and 20c and thumb member D may be stitched to the back section C in lieu of being adhesively secured, in which instance, the covering of lead impregnated tape will also act to seal the needle openings left by the stitching operation.

While I have shown and described what I consider to be the most practical embodiment of my invention, I wish it to be understood that such changes in construction as come within the scope of the appended claims may be resorted to if desired.

Having thus described the invention, what I claim as new and desire to secure by Letters Patent of the United States, is:

1. An X-ray proof glove comprising a trunk constructed of lead impregnated rubber folded lengthwise upon itself to provide front and back glove sections, stitching flatly securing the free corresponding side edges and free finger edges of the folded glove sections together, and a lead impregnated rubber binding strip folded over the stitched edges and stitching and adhesively secured to adjacent portions of the front and back glove sections for ray-proofing the needle openings in the sections caused by stitching.

2. In an X-ray proof glove constructed of flexible X-ray proof material, a front glove section having four front finger portions and a thumb opening, a rear glove section integral with the front glove section along one of its sides and having spaced first and fourth finger portions integral therewith which are disposed in opposed relation to the first and fourth front finger portions and being of a width and height slightly greater, second and third rear finger portions secured to the top edge of the rear glove section and being disposed in the space between the rear first and fourth finger portions, and being slightly wider and longer than the opposed front, second and third finger portions, a thumb member extending outwardly through the thumb opening and having its lower edge secured to the front glove element adjacent the edges of said thumb opening, lines of stitching securing the meeting side edges of the front and rear glove sections together and securing the free meeting edges of the front and rear finger portions together, and flexible X-ray proof tape extending about and folded over the stitched edges and secured thereto to seal the needle openings therein.

3. In an X-ray proof glove as set forth in claim 2 in which the lower edge of the thumb member and adjacent edge of the front glove element about the thumb opening are scived, an adhesive substance securing the scived edges of the thumb member and thumb opening together, and a strip of X-ray proof tape overlying the joint between the thumb member and the front

glove element and adhesively secured thereto to ray-proof and reinforce said joint.

4. In an X-ray-proof glove as set forth in claim 2, including a strip of X-ray proof material overlying the outer side joints between the second and third front finger portions and the rear glove element and adhesively secured thereto for ray-proofing and reinforcing the said joints.

5. The method of making an X-ray proof glove which consists in applying a fabric lining sheet to one side of a sheet of lead impregnated rubber and adhesively securing the same thereto, applying a second sheet of lead impregnated rubber flat against the other side of the first sheet of rubber, cutting the two rubber sheets and lining sheet to provide a trunk, folding the fabric lining side of the trunk upon itself on a medial line lengthwise thereof, and securing the complementary free side and free finger edges of the folded trunk together.

6. The method of making an X-ray proof glove which consists in applying a fabric lining sheet to one side of a sheet of lead impregnated rubber and adhesively securing the same thereto, applying a second sheet of lead impregnated rubber flat against the other side of the first sheet of rubber, cutting the two rubber sheets and lining sheet to provide a trunk, folding the fabric lining side of the trunk upon itself on a medial line lengthwise thereof, and securing the oppositely disposed free side and free finger edges of the folded trunk together by lines of stitching, and sealing the needle openings caused by stitching with lead impregnated rubber.

7. The method of making an X-ray proof glove which consists in providing an inner X-ray proof glove member, the successive steps of which consist of adhesively securing a fabric lining sheet to one side of a sheet of lead impregnated rubber, applying a second sheet of lead impregnated rubber flat against the other side of the first sheet of rubber, simultaneously cutting the two rubber sheets and lining sheet to provide a trunk having a front glove section and a rear glove section, slitting the front glove section, setting an inner fabric lined X-ray proof thumb receiving element into the slit and securing the same to the front glove section adjacent the edges of the slit, folding the fabric lining side of the front and rear glove sections inwardly upon themselves, stitching the meeting corresponding edges of the free sides and meeting free edges of the finger portions of the front and rear glove sections together, inserting the inner X-ray glove into a complementary outer leather glove, and stitching the inner X-ray proof glove and outer leather glove together adjacent the edges of the hand entrance openings thereof.

8. In an X-ray proof article having two separate complementary sheets of lead impregnated rubber, said sheets of rubber being superposed with their inner sides flatly abutting adjacent the corresponding free side edges, lines of stitching passing through the free side edges to secure the sheets together at the said side edges, and a binding strip of lead impregnated rubber of substantially U-shape in cross section disposed about the exterior of the side edges and overlying the lines of stitching on the outer sides of said sheets, and an adhesive connection between the binding strip and the outer sides of the sheets for securing the binding strip thereto to effect a reenforcement of the edges of the sheets and

X-ray-proof the holes therein caused by said stitching.

9. An X-ray proof glove having a hand portion and a forearm portion constructed from a trunk comprising two relatively thin like plies of lead impregnated sheets of rubber, said trunk being folded upon itself with the opposed corresponding side edges in alinement, stitching flatly securing the free alined edges of the trunk together, and a lead impregnated rubber binding strip folded over the stitched edges and stitching and adhesively secured to opposite sides of the folded trunk to ray-proof the needle openings in the trunk caused by the stitching.

10. An X-ray proof glove including comple- 15

mentary front and back glove sections integrally connected along one of their sides having free alined edges along their other sides, each of said sections being constructed from relatively thin inner and outer plies of lead impregnated sheet rubber, said front and back glove sections having corresponding finger portions provided with free alined edges, stitching securing the free alined edges of the glove sections flatly together and the free finger portion edges flatly together, and a lead impregnated rubber binding strip of U-shape in cross section overlying the stitching and adhesively secured to adjacent edge portions of the front and back glove sections.

MORRIS LUBOW.
